(57) **CLAIM**

We claim the ornamental design for a disposable tool, as shown and described.

DESCRIPTION

FIG. 1 is a bottom, front, left perspective view of the claimed design;

FIG. 2 is a top, rear, right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof; and,

FIG. 8 is a right elevation view thereof.

The ornamental design which is claimed is shown in solid lines in the drawings.

The broken lines in the drawings form no part of the claimed design. Broken lines formed by equal length dashes show unclaimed subject matter. Broken lines formed of unequal length dashes (i.e., dash-dot) define bounds of the claimed design.

The disposable tool is shown with a symbolic break in its length. The appearance of any portion of the article between the break lines forms no part of the claimed design.

The unshaded areas form no part of the claim.
